TUNING INDICATOR FOR RADIO RECEIVERS

Joseph A. Briggs, Erlton, N. J., assignor to Philco Radio & Television Corporation, Philadelphia, Pa., a corporation of Delaware

Application April 27, 1936, Serial No. 76,669

13 Claims. (Cl. 116—124.4)

This invention relates to tuning indicators for radio receivers and the like apparatus, the principal object of the invention being to provide an improved device of this class which is simple 5 in construction, efficient in operation, and adapted to perform the functions hereinafter specifically set forth.

A more specific object of the invention is to provide an improved tuning indicator device 10 wherein a light image is formed upon a dial and there is provided means for sharply defining the image and for substantially eliminating background shadows.

Another object of the invention is to provide 15 a simple and inexpensive means in the form of a light-transmitting cylindrical member arranged cooperatively with certain other elements of the device to effect the above-stated functions.

Still another object of the invention is to provide 20 a tuning indicator of this character which is adapted for use in a radio receiver of the type employed to receive signals in a plurality of different frequency bands, such a receiver being 25 commonly referred to as a "multi-band receiver".

Other objects and features of the invention will appear hereinafter.

In the accompanying drawings, wherein there 30 is illustrated a preferred form of the invention,

Fig. 1 is a side elevational view of the device shown in cooperative relation with certain parts of a radio receiver;

Fig. 2 is a plan view of the device;

Fig. 3 is a fragmentary perspective view illustrating more clearly the elements of the device and their cooperative relation;

Fig. 4 is a fragmentary face view of the device;

Fig. 5 is a sectional view taken along line 5—5 of Fig. 1; and

Fig. 6 is a diagrammatic illustration of the manner of operation of the device.

Referring particularly to Figs. 1 and 2 of the drawings, a support 1 carries a frame 2 which, in turn, supports the usual variable tuning condensers 3 of the radio receiver, as well known. The rotatable shaft 4 of the tuning condenser assembly carries a gear 5 which meshes with a small gear 6 affixed to the inner end of the manually operable shaft 7, the outer end of this shaft carrying a control knob 8. The tuning condenser shaft 4 also carries a gear 9 which meshes with a gear 10 rotatably mounted on a stud 11 secured to the front wall 12 of frame 2.

A hub structure 13 is secured to gear 10 so as to be rotatable therewith and carries a translucent tuning dial 14. It will be seen, therefore, that rotation of the shaft 7 through the medium of control knob 8 rotates the tuning condenser shaft 4 through gears 5 and 6 and also rotates the tuning dial 14 through gears 9 and 10.

A bracket 15 is supported by frame 2 and, in turn, supports a bracket 16 upon which there is mounted a lamp structure 17. The lamp structure includes a reflector 18 surrounding the lamp 19 so as to direct the light rays in a desired direction as will be more clearly understood later. The bracket 15 carries a frame 20 having a window opening therein, as shown more clearly in Fig. 3. A light-transmitting cylindrical member 21, which preferably takes the form of a glass rod, is disposed centrally of the frame 20 and carried thereby. To this end, there are provided on frame 20 upper and lower lugs 22 adapted to seat the member 21 and the said member is removably secured in place by means of resilient members 23, the ends of which are removably secured by lugs 24 provided on the frame 20. The members 23 may conveniently comprise pieces of resilient wire or the like. A translucent screen or plate 25 is also secured to the frame 20 and covers the window openings thereof, as clearly illustrated in Fig. 3 wherein the upper portion of the translucent screen is broken away for clarity of illustration. At its central portion, the translucent screen 25 is provided with a slot-like aperture 26 which is axially aligned with the cylindrical member 21. The aperture 26 constitutes an area of greater light-transmitting characteristic than the remaining area of screen 25. While it is preferred to employ an aperture, it will be appreciated that the screen may be formed of materials having different light-transmitting characteristics to provide the desired area, or other methods may be employed.

It will be seen that the translucent screen 25 is stationary and, as shown more clearly in Fig. 5, this screen is arranged behind the movable translucent dial 14 and the cylindrical member 21 is interposed between dial 14 and screen 25. It will also be seen that the screen 25 is interposed between dial 14 and the light source 19, and there is formed upon the translucent dial 14 a light image having the shape of a narrow line of light. This light image is formed on dial 14 by means, first, of the greater light-transmitting characteristic of the aperture 26 compared to the light-transmitting characteristic of the remaining area

of the translucent screen 25 and, second, the focusing action of the member 21. The light transmitted through the screen 25 and dial 14 forms an illuminated background for the light image, the image being distinctly brighter than the background. The cylindrical member 21 serves to more sharply define the light image and to substantially eliminate background shadows, as will be explained more fully hereinafter.

For use in multi-band receivers of the type above mentioned, there is provided between the translucent screen 25 and the light source 19 a second translucent screen 27. This second screen is carried by a support 28 which is loosely mounted upon the hub of gear 10, so that the support 28 and the screen 27 carried thereby are freely rotatable as a unit. The screen 27 is provided with arcuate openings 29, as shown in Fig. 3, which are arranged cooperatively with the respective sets of graduations upon the dial 14 shown clearly in Fig. 4. As will be well understood, the concentric sets of indicia or graduations upon dial 14 designate different wave bands or frequency bands to which the radio receiver 25 is receptive. Although the screen 27 is broken away in Fig. 3 for clarity of illustration, it will be understood that there will be an aperture 29 for each of the different sets of indicia on dial 14. It will be seen also that the apertures 29 are spaced from one another angularly and also radially, the radial spacing of these apertures corresponding to the radial spacing of the sets of indicia on dial 14. It will be seen, therefore, that by rotating the screen 27 any desired one of the apertures 29 may be brought into position behind the elongated slot 26 for use in conjunction with the corresponding set of indicia on dial 14 when it is desired to operate the receiver to receive broadcast signals within the particular frequency range or wave band. The aperture 29, which is thus positioned behind the elongated slot 26, defines a background area for the above-mentioned image, which area is more brilliantly illuminated than the remaining background area and stands out in contrast therewith but is less brilliantly illuminated than the image formed by slot 26. Moreover, the aperture 29 serves to confine the indicating image to the particular set of indicia on dial 14 being used in the particular instance.

The support 28 has connected thereto a link 30 (see Fig. 1), the lower end of which is connected by a crank arm 31 to the front end of the rotatable shaft 32 forming a part of the wave band switch 33. As the wave band switch is a conventional element of the multi-band receiver, it is unnecessary to illustrate or describe such device in detail, it being sufficient to note that this device adapts the radio receiver for reception in any one of the several frequency bands or wave bands and is actuated by rotation of the shaft 32. The shaft 32 is manually operable by virtue of the control knob 34. It will be seen, however, that rotation of the shaft 32, through the medium of knob 34, in addition to actuating the wave band switch, rotates the screen 27 through the medium of link 30, the parts being so arranged or designed that the aperture 29 corresponding to a particular position of the wave band switch is brought into position behind slot 26 when the switch is actuated to that position.

The translucent members 14, 25 and 21 may be formed of any suitable translucent material, such as that of which the translucent dials of tuning devices for radio receivers are commonly made. These members may be readily cut or

stamped from sheets of material, as will be well understood. As stated above, the cylindrical member 21 may be formed of glass rod and may be simply cut from a length of rod of the desired diameter.

The operation of the device is illustrated diagrammatically in Fig. 6. In this illustration, the parts are greatly enlarged to illustrate the action more clearly. Light rays passing through the central part of slot 26 along the axis o will pass through the light-transmitting cylindrical member and will converge or be brought to a focus upon the translucent dial 14 at point p. Light rays passing through the slot 26 on opposite sides of the axis o, such as those illustrated at a, b, c, 15 a', b' and c', will be bent upon passing into the cylindrical member 21, as clearly illustrated, and upon leaving the member 21 will be further bent and will converge or be brought to a focus substantially at the point p. Thus, the light rays which pass through the slot 26 are refracted and brought to a focus by the cylindrical member 21 in a line passing through point p and perpendicular to the plane of the paper as viewed in Fig. 6. In other words, these light rays will be 25 brought to sharp focus in a line upon the translucent dial 14, so that a sharply defined line of light is formed upon the dial and the indicia on the dial may be brought into accurate coincidence with this line-like image, thus enabling 30 accurate and easy tuning of the receiver.

Light rays, such as those shown at d' and d'', which pass through the screen 25 near aperture 26 are refracted as illustrated and brought to a focus at point m spaced from point p. In like 35 manner, light rays which are further removed from slot 26, such as those illustrated at e and e', will be refracted and brought to a focus at a point n still further removed from point p. These light rays, however, will impinge upon the dial 14 and 40 will form a substantially shadowless background for the sharply defined image above mentioned.

In general, light rays entering the cylindrical member on a path parallel to the axis will come to a focus at a point on the axis which will depend upon the distance between the path of the incoming ray and the axis. Where this distance is small, that is, where the ray path is close to the axis, the ray will come to a focus or cross the axis at a point dependent largely upon the 50 index of refraction of the focusing member, the point being one-half the radius away from the surface of the cylindrical member for the case in which the index of refraction of the member is 1.50 which is the approximate value for common glass. Rays entering the rod parallel to the axis but a greater distance away from it will cross the axis on the other side at a point nearer the surface, the distance of this point from the surface being nearly one-half the radius for a 60 glass rod in the case in which the distance of the incoming rays from the axis is less than one-half the radius of the rod, such as rays a, b, and c, while for rays such as d, e for which the latter distance is greater than one-half the rod radius, 65 the distance between the intersection of the ray with the axis and the surface of the rod will be considerably less than one-half the rod radius.

Advantage is taken of this peculiar focusing characteristic of a cylindrical rod to form the 70 desired line of light without the usual shadow formed by light focusing means. By positioning the translucent dial at a point slightly less than one-half the rod radius from the surface of the rod, all of the light entering the rod less than 75

about one-half the rod radius from the axis is made to converge upon a narrow line on the dial member and thus serves to define a sharp line of light thereon. Now light passing through the 5 translucent screen 25 away from the rod, such as ray *f*, will be diffused and broken up by the screen to form rays, such as *g*, *h*, *j*, *k*, *l* which serve to illuminate the dial 14 generally. These rays will, of course, be considerably diminished 10 in intensity due to the poor light transmission properties of the translucent screen. These rays serve to form the general illumination of the whole window as indicated by the dotted line in Fig. 4. It will be seen, however, that the rod 15 would tend to cast a shadow upon the dial 14 between the generally illuminated area and the bright line of light except for the peculiar focusing action of the rod which causes rays such as *d* and *e* to converge more completely and thus 20 impinge on the dial in this inbetween region. This effect is further augmented by the fact that light passing through the screen 25 is diffused, and thus rays such as *d* and *e* will be modified in passing through the screen and will enter 25 the rod along several different directions as shown in Fig. 6. For the sake of simplicity, only one path (*d*, *e*) is shown for each ray diffused by the screen 25, but it will be understood that the other diffused rays will pass through the rod, 30 be refracted as indicated by other rays, and eventually impinge on the dial 14.

It will be noted that the width of the aperture 26 will not have much effect upon the width of the light image, but simply serves to control the 35 total amount of light which is brought to the sharp focus. The width of the light image is determined by the distance of the dial from the rod, and as indicated, the narrowest line may be obtained when the dial is positioned slightly less 40 than one-half the rod radius from the surface of the rod. As described more clearly below, the invention provides means for holding the dial in this preferred position as the dial itself is moved.

In the above discussion no mention has been 45 made of the screen 27. Where light passes through an aperture 29 in the screen 27, the focusing of the light by the several means will be as described and a short bright line of light formed as indicated in Fig. 4. Light passing 50 through the translucent screen 27 rather than through an aperture in the screen will, however, be diminished in intensity and will further be diffused by the screen. Thus, an area generally similar to the aperture 29 will be outlined on 55 the dial as indicated in Fig. 4. Now the focusing action of the rod depends upon having the light passing through the aperture 26 do so along paths generally parallel to the axis *o* (Fig. 6), and while this requirement is not sufficiently critical to 60 make it necessary to put the light source in any one particular spot, nevertheless, the screen 27 will sufficiently diffuse the light so that light passing through this screen will not be brought to a focus by the other means and thus the length 65 of the line of light on the dial 14 will be determined by the width of the aperture 29 through which light is transmitted to the rod and screen 25 and by proper design this line of light may be arranged to cover only one wave band on the dial, and a section of this band on each side of the line of light may be illuminated somewhat 70 more brightly than the remaining area, as indicated in Fig. 4. It is worthy of note that as the large portion of light transmitted through the 75 dial 14 is of diffused character, the general ap-

pearance of the dial will be of pleasing quality, and the user may easily adjust the tuning of the receiver without irritation to his eyes.

Thus, the cylindrical member 21, in cooperative arrangement with the slotted screen 25, 5 serves to produce a sharply defined image on dial 14 and also serves to substantially eliminate shadows from the background surrounding the image. It will be understood, of course, that the member 21 should be properly related in diameter 10 to the width of slot 26, but these dimensions may vary somewhat relative to one another. Preferably, the slot 26 should not be greater in width than the radius of the cylindrical member 21. The index of refraction of material of which the 15 member 21 is formed will, of course, have a bearing upon the functioning of the device but, in general, any common glass or similar material may be used. It will be understood, of course, that the invention is not limited to the dimensions or materials herein specifically mentioned, 20 as it is possible to design the device to obtain varying effects.

In order to maintain the dial 14 in proper relation to the member 21, there are provided on 25 the frame 20 support and guide projections 35 having raised nubs 36 thereon (see Figs. 3 and 4) which projections extend around the edge of the dial to the front thereof, and there are also provided on frame 20 nubs 37 (see Figs. 1 and 4) 30 disposed behind the dial. The front nubs 36 and the rear nubs 37 thus seat and guide the portion of dial 14 adjacent frame 20 and maintain that portion of the dial parallel to and in fixed relation with the axis of member 21. Moreover, this 35 light-receiving portion of the dial is thus kept flat and presents a uniform surface to the light passing through screens 25 and 27.

From the illustration and above description, it will be seen that the device provided by the invention is of simple construction and may be 40 economically manufactured, and it will also be seen that it embodies a novel combination or arrangement of parts which serve cooperatively to produce a sharp line-like image upon the indicator dial with a substantially shadowless background for the image. It will be understood, of course, that the invention is not limited to the specific form illustrated and that various changes and modifications may be made without departing 45 from the scope of the invention as defined by the appended claims.

I claim:

1. A tuning indicator for radio receivers or the like, comprising a movable translucent dial having indicia thereon, a source of light, a translucent screen interposed between said dial and said light source, said screen having an area of different light-transmitting characteristic from the remaining area of the screen, and focusing means 55 cooperatively associated with said area for producing a sharply defined image upon said dial with which said indicia may be made to coincide by moving said dial.

2. A tuning indicator for radio receivers or the 60 like, comprising a movable translucent dial having indicia thereon, a source of light, a translucent screen interposed between said dial and said light source, said screen having an area of different light-transmitting characteristic from the 65 remaining area of the screen, and focusing means interposed between said screen and said dial, adjacent said area and the portion of said screen thereabout, for producing a sharply defined image upon said dial with which said indicia may be 70 75

made to coincide by moving said dial and for substantially eliminating background shadows.

3. A tuning indicator for radio receivers or the like, comprising a movable translucent dial having indicia thereon, a source of light, a translucent screen interposed between said dial and said light source, said screen having an elongated area of different light-transmitting characteristic from the remaining area of the screen, and a light-transmitting member having opposed cylindrical surfaces, cooperatively associated and axially aligned with said area, for producing a sharply defined image upon said dial with which said indicia may be made to coincide by moving said dial.

4. A tuning indicator for radio receivers or the like, comprising a movable translucent dial having indicia thereon, a source of light, a translucent screen interposed between said dial and said light source, said screen having an elongated area of different light-transmitting characteristic from the remaining area of the screen, and a light-transmitting cylindrical member, cooperatively associated and axially aligned with said area, for producing a sharply defined image upon said dial with which said indicia may be made to coincide by moving said dial.

5. A tuning indicator for radio receivers or the like, comprising a movable translucent dial having indicia thereon, a source of light, a translucent screen interposed between said dial and said light source, said screen having an elongated area of different light-transmitting characteristic from the remaining area of the screen, and a light-transmitting cylindrical member interposed between said screen and said dial, and axially aligned with said area and the portion of said screen thereabout, for producing a sharply defined image with which said indicia may be made to coincide by moving said dial and for substantially eliminating background shadows.

6. A tuning indicator for radio receivers or the like, comprising a movable translucent dial having indicia thereon, a source of light, a translucent screen interposed between said dial and said light source, said screen having an elongated area of different light-transmitting characteristic from the remaining area of the screen, and a light-transmitting cylindrical member interposed between said screen and said dial, and axially aligned with said area and the portion of said screen thereabout, for producing a sharply defined image upon said dial with which said indicia may be made to coincide by moving said dial and for substantially eliminating background shadows, said member having a diameter at least twice as great as the width of said area.

7. A tuning indicator for radio receivers or the like, comprising a movable translucent dial having indicia thereon, a source of light, a supporting frame interposed between said dial and said light source, a translucent screen carried by said frame, said screen having an area of different light-transmitting characteristic from the remaining area of the screen, and a light-transmitting member carried by said frame in cooperative association with said area for producing a sharply defined image upon said dial with which said indicia may be made to coincide by moving said dial.

8. A tuning indicator for radio receivers or the like, comprising a movable translucent dial having indicia thereon, a source of light, a translucent screen interposed between said dial and said light source, said screen having an area of

different light-transmitting characteristic from the remaining area of the screen, a light-transmitting member cooperatively associated with said area for producing a sharply defined image upon said dial with which said indicia may be made to coincide by moving said dial, and means for maintaining said dial in proper relation to said member.

9. A tuning indicator for radio receivers or the like, comprising a movable translucent dial having indicia thereon, a source of light, a supporting frame interposed between said dial and said light source, a translucent screen carried by said frame, said screen having an area of different light-transmitting characteristic from the remaining area of the screen, a light-transmitting member carried by said frame in cooperative association with said area for producing a sharply defined image upon said dial with which said indicia may be made to coincide by moving said dial, and means on said frame for maintaining said dial in proper relation to said member.

10. A tuning indicator for radio receivers or the like, comprising a movable translucent dial having indicia thereon, a source of light, a supporting frame interposed between said dial and said light source, a translucent screen carried by said frame, said screen having an area of different light-transmitting characteristic from the remaining area of the screen, a light-transmitting member carried by said frame in cooperative association with said area for producing a sharply defined image upon said dial with which said indicia may be made to coincide by moving said dial, and a plurality of nubs on said frame on opposite sides of said dial for maintaining said dial in proper relation to said member.

11. A tuning indicator for a multi-band radio receiver, comprising a movable translucent dial having different sets of indicia thereon, a source of light, a translucent screen interposed between said dial and said light source, said screen having an elongated area of different light-transmitting characteristic from the remaining area of the screen, a movable translucent screen also interposed between said dial and said light source, and having spaced areas of different light-transmitting characteristic from the remaining area of the screen, said areas corresponding respectively to said different sets of indicia and being adapted to be brought into cooperative relation with said elongated area by moving said last-mentioned screen, and focusing means cooperatively associated with said elongated area for producing a sharply defined image upon said dial with which said indicia may be made to coincide by moving said dial.

12. A tuning indicator for a multi-band radio receiver, comprising a movable translucent dial having different sets of indicia thereon, a source of light, a translucent screen interposed between said dial and said light source, said screen having an elongated area of different light-transmitting characteristic from the remaining area of the screen, a movable translucent screen also interposed between said dial and said light source, and having spaced areas of different light-transmitting characteristic from the remaining area of the screen, said areas corresponding respectively to said different sets of indicia and being adapted to be brought into cooperative relation with said elongated area by moving said last-mentioned screen, and a light-

transmitting member having opposed cylindrical surfaces, cooperatively associated and axially aligned with said elongated area, for producing a sharply defined image upon said dial with which said indicia may be made to coincide by moving said dial.

13. A tuning indicator for a multi-band radio receiver, comprising a movable translucent dial having different sets of indicia thereon, a source 10 of light, a translucent screen interposed between said dial and said light source, said screen having an elongated area of different light-transmitting characteristic from the remaining area of the screen, a translucent screen also interposed between said dial and said light source,

and having spaced areas of different light-transmitting characteristic from the remaining area of the screen, said areas corresponding respectively to said different sets of indicia and being adapted to be brought into cooperative relation with said elongated area by moving said last-mentioned screen, and a light-transmitting cylindrical member, cooperatively associated and axially aligned with said elongated area and the portion of said first screen thereabout, for producing a sharply defined image upon said dial with which said indicia may be made to coincide by moving said dial and for substantially eliminating background shadows.

JOSEPH A. BRIGGS. 15
